US0D1083240S

(12) United States Design Patent (10) Patent No.: US D1,083,240 S
(45) Date of Patent: * Jul. 8, 2025

(54) FACEGUARD

(71) Applicant: Warren Martin Hill, Glen Burnie, MD (US)

(72) Inventor: Warren Martin Hill, Glen Burnie, MD (US)

() Term: 15 Years

(21) Appl. No.: 29/981,559

(22) Filed: Dec. 31, 2024

Related U.S. Application Data

(63) Continuation-in-part of application No. 29/917,013, filed on Nov. 16, 2023, which is a continuation-in-part of application No. 29/803,414, filed on Aug. 12, 2021, now abandoned.

(57) CLAIM

The ornamental design for a faceguard, as shown and described.

DESCRIPTION

FIG. 1 is a front-top-right perspective view of a faceguard showing my new design;

FIG. 2 is a front-bottom-left perspective view thereof;

FIG. 3 is a rear-top-right perspective view thereof;

FIG. 4 is a rear-bottom-left perspective view thereof;

FIG. 5 is a front elevational view thereof;

FIG. 6 is a rear elevational view thereof;

FIG. 7 is a right elevational view thereof;

FIG. 8 is a left elevational view thereof;

FIG. 9 is a top plan view thereof; and,

FIG. 10 is a bottom plan view thereof.

The broken lines shown illustrate portions of the faceguard which form no part of the claimed design.

1 Claim, 10 Drawing Sheets
